UNITED STATES PATENT OFFICE

147,745

DESIGN FOR A PORTABLE PASSENGER LOADING PLATFORM

Philip G. Dorrlar, Malverne, N. Y., assignor to Republic Aviation Corporation, near Farmingdale, N. Y., a corporation of Delaware

Application March 12, 1946, Serial No. 127,399

Term of patent 14 years

(Cl. D14—3)

To all whom it may concern:

Be it known that Philip G. Dorrlar, a citizen of the United States and a resident of Malverne, in the county of Nassau and the State of New York, has invented a certain new, original, and ornamental Design for Portable Passenger Loading Platform, described and claimed in the following specification and shown in the accompanying drawings wherein:

Fig. 1 is a perspective view of a passenger loading platform embodying the present design and shows the same at one extreme of its adjustment and the control at one end of the device exposed and that at the other end retracted;

Fig. 2 is a perspective view thereof taken from the opposite end showing the other extreme of the adjustment of the device;

Fig. 3 is a plan view thereof with the controls at the ends of the platform retracted;

Fig. 4 is an end elevation thereof with the control retracted; and

Fig. 5 is a side elevation thereof also with the controls retracted.

What is claimed is:

The ornamental design for a portable passenger loading platform, substantially as shown.

PHILIP G. DORRLER.
